[57] CLAIM

The ornamental design for a roofless canopy for use above a retail sales counter, or similar article, substantially as shown and described.

DESCRIPTION

FIG. 1 is a front and right side perspective view of a roofless canopy for use above a retail sales counter, or similar article showing our new design.

FIG. 2 is a front elevational view;

FIG. 3 is a left side elevational view;

FIG. 4 is a right side elevational view;

FIG. 5 is a bottom plan view;

FIG. 6 is a top plan view; and

FIG. 7 is a rear elevational view.
